PROTECTIVE GLOVE

Lawrence E. Dickson, Chicago, Ill.

Application December 17, 1934, Serial No. 757,966

1 Claim. (Cl. 2—161)

This invention relates to protective gloves and more particularly to a heat-insulating leather glove adapted for use by welders and the like.

The primary object of the invention is to provide a glove which will protect the wearer's hand from intense heat, such as developed by welding operations and the like, but will not be rendered unserviceable through shrinkage of the leather.

Heretofore welder's gloves were constructed of substantially the same size as any other work-glove and frequently it would be necessary to discard comparatively new gloves because the heat caused the material in the little finger to shrink so much that it was impossible for the operator to get his hand into the same. The same difficulty has been noted in other fields such as riding gloves. After being worn a few times the leather in the little finger, which often rubs on the sweaty neck of the horse, shrinks and becomes unserviceable.

In describing the present invention it is necessary to compare the improved glove with what may be called a normal glove, i. e., a standard glove adapted to fit the hand of a workman and constructed with all of the fingers of approximately the same circumference.

The invention is illustrated in the preferred embodiment in the accompanying drawing in which A designates the hand portion of a glove or gauntlet, B the wrist portion to which may be connected a sleeve protecting portion C, and E finger-portions.

Usually the hand and finger portions are formed integrally by stitching together two or more pieces of material along the seams 10. The thumb portion 11 which may be considered as one of the fingers may be formed in the usual manner. Preferably the gauntlet is formed so that the hand portion and wrist portion B will fit the hand of a wearer with comfortable snugness.

The sleeve portion C may be stitched to the wrist portion as indicated at 12 and may be formed of leather or any suitable fabric. Preferably it is provided with a patch 13 to reinforce that portion of the sleeve which is subjected to the greatest wear. In the embodiment illustrated the finger portion or stall 14 is adapted to enclose the right index finger of the wearer, the finger portion 15 will enclose the middle finger,

and the finger portion 16 will enclose the ring finger, or fourth finger. However, the "small" finger is cut with a lateral swell 18 at its outer side to provide an enlargement. In order to accomplish the desired results the mean circumference of the "small" finger should be at least 25% greater than that of the other fingers and preferably 50 to 100% larger. This lateral swell can be provided in making the gloves at an extremely small additional cost.

Most welders hold the welding torch and rod in their hands in such a way that the "small" finger is subjected to the greatest heat. This finger acts as a sort of shield for the rest of the glove and as a result the material, preferably chrome-leather, dries out very rapidly and causes the finger to shrink in circumference. Of course, the thumb 11 or finger 14 might be enlarged where that side of the glove was to be subjected to the heat but it is desirable to have the other fingers fit snugly and comfortably in order that small articles may be picked up with the gloved hand and the glove will not interfere appreciably with the hand movements of the wearer. The finger 16 might be enlarged but this is generally unnecessary, for, as stated above, the little finger usually acts as a shield. Another advantage of having the large finger 17 for the smallest finger of the operator is in that it provides a large air space around the finger to insulate and protect the finger of the operator.

The foregoing detailed description has been given for clearness of understanding only, and no unnecessary limitations should be understood therefrom, but the appended claim should be construed as broadly as permissible, in view of the prior art.

I claim:

A heat-insulating glove adapted for use by welders, comprising a normal hand-portion, and normal thumb, first, second and third finger stalls; and a fourth finger stall provided with a lateral enlargement at its outer side to give said stall a mean circumference at least 25% greater than normal to provide additional air space around the fourth finger of a wearer and to allow for subsequent shrinkage.
